Primary Examiner — Katrina N Gonzalez

(57) **CLAIM**

The ornamental design for a slow feeder insert, substantially as shown and described.

DESCRIPTION

FIG. 1 is a front perspective view of a slow feeder insert, showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines illustrate portions of the slow feeder insert that form no part of the claimed design.
